UNITED STATES PATENT OFFICE.

HENRY C. FULLER, OF WASHINGTON, DISTRICT OF COLUMBIA, ASSIGNOR TO UNION CARBIDE AND CARBON RESEARCH LABORATORIES, INC., OF LONG ISLAND CITY, NEW YORK, A CORPORATION OF NEW YORK.

DENATURED ALCOHOL.

No Drawing.

Application filed June 21, 1922. Serial No. 569,951.

To all whom it may concern:

Be it known that I, HENRY C. FULLER, a citizen of the United States, residing at Washington, District of Columbia, have invented certain new and useful Improvements in Denatured Alcohol, of which the following is a specification.

My invention consists in adding to ethyl alcohol certain derivatives of polyhydric alcohols for the purpose of so denaturing the alcohol that it is no longer potable, while at the same time such denatured alcohol is suitable for use in preparing a variety of articles such as liniments, mouth washes, toilet waters, perfumes, hair tonics, bay rum and many liquid medicines such as fluid extracts, tinctures and other mixed medicines.

In my application Serial Number 475,478 filed June 6, 1921 I have disclosed the use of glycerine derivatives such as the chlorhydrins and halogen aliphatic acid derivatives of glycerine as denaturing agents for ethyl alcohol. I have now found that the derivatives of the glycols such as the halogen aliphatic acid esters of the glycols, the glycol halogen hydrins and the aliphatic and aromatic acid esters of both glycerine and glycols may be used as denaturing agents. As examples of the classes of compounds which I propose to use as denaturing agents are glycerol mono-acetate, ethylene glycol mono-acetate, the monochloracetic acid ester of ethylene glycol and the benzoic acid esters of glycerine and ethylene glycol. The use of the monochlorhydrin of glycerine and the monochloracetic-monoglyceride is referred to in my copending application referred to above.

These denaturing agents may be used in widely varying proportions. As a general rule from 6 to 12 per cent of the denaturing agent is mixed with the alcohol, the particular amount used depending upon the price of the particular denaturing agent employed, the intensity of its denaturing effect and the use to which the denatured product is to be put. Since the denaturing agents are in general more expensive than alcohol it is usually preferred to use the smallest quantity which will produce the desired denaturing effect.

Of the various materials mentioned the monochloracetic acid esters of the polyhydric alcohols and particularly the mono-

chloraceticmonoglyceride and the mono-chloracetic acid ester of ethylene glycol are preferred. It is to be understood however that the invention is not limited to the use of these specific compounds except as is required by the appended claims.

An example of a denatured alcohol product embraced by my invention is a mixture of 90 parts by volume of 95 per cent ethyl alcohol and 10 parts by volume of the mono-chloracetic acid ester of ethylene glycol.

Heretofore the work of the Bureau of Internal Revenue has been greatly complicated and the work of manufacturing ethyl alcohol greatly interfered with by the use of a great variety of denaturing agents none of which are of general application. Some of the denaturing agents heretofore employed are suitable for use in the manufacture of only one product or a limited number of products.

The use of the denaturing agents of my invention largely overcomes this difficulty. The treated alcohol is sufficiently denatured to be unfit for use as a beverage due to its unpleasant taste. Even in considerable dilution, the effect is such that when introduced into the mouth, the taker cannot swallow it. On the other hand the odor of the denaturing agent is comparatively mild and does not unpleasantly affect the aromatic substances and volatile oils which enter into the compositions referred to above. Moreover the denaturing agents are not violently poisonous and are not detrimental to alcohol preparations ingested or applied to the skin in small amounts.

The dentured alcohol containing the denaturing agents of my invention, besides being non-potable and capable of rather general application because the odor is not offensive and because the physiological properties of the denaturing agents are not detrimental to the alcohol, retains its solvent properties and its capacity for being compounded into preparations of the kind above described, and it can be diluted with water without precipitation of the denaturing agent.

It is of course understood that mixtures of two or more of the derivatives of polyhydric alcohols herein described can be used as denaturing agents without departing from my invention.

In the appended claims the expression organic acid esters is intended to include both ethyl alcohol and a chlor fatty acid ester of the aliphatic and aromatic acid esters and the expression polyhydric alcohols includes 5 alcohols containing more than one hydroxyl group such as the dihydric and trihydric alcohols.

I claim:

1. Denatured ethyl alcohol comprising 10 ethyl alcohol and a halogen fatty acid ester of a polyhydric alcohol.

2. Denatured ethyl alcohol comprising ethyl alcohol and a chlor fatty acid ester of a polyhydric alcohol.

3. Denatured ethyl alcohol comprising 15 ethyl alcohol and a chloracetic acid ester of a polyhydric alcohol.

4. Denatured ethyl alcohol comprising ethyl alcohol and a chloracetic acid ester of ethylene glycol.

In testimony whereof, I affix my signature.

HENRY C. FULLER.
